UNITED STATES PATENT OFFICE.

THEODORE GRISSINGER, OF MECHANICSBURG, PENNSYLVANIA.

CULTIVATOR.

SPECIFICATION forming part of Letters Patent No. 247,756, dated October 4, 1881.

Application filed June 18, 1881. (No model.)

To all whom it may concern:

Be it known that I, THEODORE GRISSINGER, a citizen of the United States, residing at Mechanicsburg, in the county of Cumberland and State of Pennsylvania, have invented certain new and useful Improvements in Cultivators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to that class of attaching devices for cultivator teeth or shovels in which provision is made for permitting the shovel to swing backward when it encounters an obstruction and cause it to return to its working position after the passage beyond said obstruction.

The object of the invention is to insure a firm and rigid connection between the cultivator beam or stock and the pivoted foot or shovel sleeve, whereby the cultivator shovel or tooth will perform its work in an effective and satisfactory manner, and is not liable to yield or move when working in hard ground or when clods are encountered.

To this end the invention consists in the construction and combination of parts which will hereinafter be more fully described, and then set forth in the claims.

In the drawings, Figure 1 is a side elevation of a curved cultivator-beam and the devices for attaching the shovel thereto. Fig. 2 is a rear view of said beam and shovel-attaching devices.

The letter A designates a metal cultivator-beam, the lower or curved portion of which serves as a stock or standard for the attachment and support of a shovel foot or sleeve, B. The latter embraces the standard or beam, and is pivoted thereto by a pivot-pin, a, passing through the shovel-foot at or about the center thereof. A shovel or tooth of any approved form or size is secured to the foot or sleeve by means of a bolt and nut, b, or other suitable fastening medium.

An arm, C, consisting of two plates extending from the rear of the shovel foot or carrier at each side thereof, and forming a rigid part of said foot, is provided with several holes, d,

which are arranged in the arc of a circle or in a curved line, as is shown in Fig. 1.

A pair of parallel plates, D, arranged on either side of the shovel-beam or standard, and a link or plate, E, fitted between said parallel plates, and connected with the arm C of the shovel-carrier, constitute a toggle-lever which is free to move in an outward direction from the standard or beam when the shovel foot or carrier is turned on its pivot-pin by the action of a stone or other obstruction. The plates D are pivoted to the standard by a pin, f, passing through the latter and the upper ends of the former, and a pin, g, fitted through said plates at or near their lower ends, serves to effect a pivotal connection of the link or plate E with the other plates or members, D, of the toggle-lever. A vertical rod or stem, F, pivoted between the plates D, at the rear of the same, extends in an upward direction, and passes through a guide bracket or arm, G, of the shovel-beam. Said rod F is encircled by a spiral or india-rubber spring, H, which is retained or held between a screw nut or collar, I, on the rod and the guide-bracket on the beam. A portion of the rod F is screw-threaded, and the screw-nut I, which is employed for adjusting the tension of the spring, is adjustable on said screw-threaded portion, and is prevented from passing below the same by a suitable projection or enlargement on the rod.

A set-screw, J, passing through the link or plate E, above the point of connection thereof with the plates D, bears against the rear edge of the beam or standard, and is employed for adjusting the toggle-lever, so as to cause it to conform to the position or angle of the shovel foot or carrier.

It will be manifest that the spring carried by the guide stem or rod exerts a downward pressure, which is transmitted to the toggle-lever, causing the latter to maintain the straightened position shown in Fig. 1. The toggle-lever being directly connected with the shovel foot or carrier, it necessarily follows that the latter is held in a firm and rigid position, so as to cause the shovel or other cultivating or plowing implement to pass through all kinds of ground in a perfect and satisfactory manner.

It frequently happens that plows or shovels

connected with their standards by wooden break-pins yield or are thrown out of a working position by clods or hard ground, and the same result also takes place with many of the cultivator-teeth heretofore devised which depend upon a spring and connecting devices for holding the same in a working position. My invention obviates the defects of devices of the latter description by locating the pressure-exerting devices at or near the shovel, or at the place where it is needed the most.

It will be obvious that the shovel can only swing backward when an obstruction is brought in its path that is sufficient to overcome the pressure of the spring and the devices connected with the shovel foot or sleeve. For example, a stone or stump or other hard object liable to injure the shovel will cause the latter to pass out of a working position, but clods or other objects which can be penetrated by the shovel will not effect the result mentioned.

The shovel-foot can be set at various angles by shifting the pivot-pin of the connecting-link or plate E into either of the holes in the arm of the shovel-foot. By placing said holes in the arc of a circle, as shown, it obviates the necessity of changing the toggle lever, as the three pivotal points are always in the same line.

The set-screw is chiefly intended to prevent the toggle-lever (through wear or other cause) from getting into a "dead-lock," which result would take place if the three pivotal points were located in a straight line.

It will be apparent that the pin passing through the link E and plates D is a little above the line of the pin f, which connects said plates with the standard and the pin d of the arm C. Hence it will be necessary to move

the set-screw whenever the parts are adjusted, so as to prevent the same from getting into a straight position and forming a dead-lock, and preventing the shovel from yielding when it strikes an obstruction. By placing the spring or pressure devices in rear of the beam the front of the same is entirely clear, which is a great advantage in cultivating grassy or manured land.

I disclaim the broad idea of combining a spring-pressed toggle-lever with a pivoted cultivator-standard, said toggle-lever being arranged horizontally on the top of the cultivator-beam.

Having thus described my invention, what I claim as new, and desire to secure by Letters Patent, is—

1. The combination of a vertical toggle-lever, having a suitable spring connected therewith, with a pivoted shovel shoe or support and the upright portion of a curved cultivator-beam, all constructed and arranged substantially as herein set forth.

2. The combination of a vertically-arranged toggle-lever and a vertical guide stem or rod, having encircling spring, with a curved cultivator-beam, having the upper end of the toggle-lever pivoted to its upright portion, and a shovel shoe or support connected with the lower end of said toggle-lever, as and for the purpose specified.

In testimony whereof I affix my signature in presence of two witnesses.

THEODORE GRISSINGER.
